UNITED STATES PATENT OFFICE.

WILLIAM EDGAR ABBOTT, OF BEND, OREGON, ASSIGNOR TO ABBOTT, INCORPORATED, OF BEND, OREGON, A CORPORATION OF OREGON.

DESIGN FOR A TALCUM-POWDER BOX.

60,206.

Specification for Design.

Patented Jan. 17, 1922.

Application filed October 3, 1921. Serial No. 505,200. Term of patent 14 years.

To all whom it may concern:

Be it known that I, WILLIAM E. ABBOTT, a citizen of the United States, residing in Bend, in the county of Deschutes and State of Oregon, have invented a new, original, and ornamental Design for a Talcum-Powder Box, (Case "B,") of which the following is a specification, reference being had to the accompanying drawings, forming a part thereof, and of which—

Figure 1 is a perspective view, and Fig. 2 is a plan view of a talcum powder box showing my new design.

I claim:

The ornamental design for a talcum powder box, substantially as shown.

WILLIAM EDGAR ABBOTT.
